S. B. WERTHEIMER.
VANITY CASE AND BOUQUET HOLDER.
APPLICATION FILED MAR. 13, 1922.

1,418,760.

Patented June 6, 1922.

INVENTOR.
Sydney B. Wertheimer
BY
Sydney B. Perry
ATTORNEY

UNITED STATES PATENT OFFICE.

SYDNEY B. WERTHEIMER, OF BROOKLYN, NEW YORK.

VANITY CASE AND BOUQUET HOLDER.

1,418,760.

Specification of Letters Patent. Patented June 6, 1922.

Application filed March 13, 1922. Serial No. 543,165.

To all whom it may concern:

Be it known that I, SYDNEY B. WERTHEIMER, a citizen of the United States of America, and resident of Brooklyn, in the county of Kings and State of New York, have invented certain new and useful Improvements in a Vanity Case and Bouquet Holder, of which the following is a specification.

10 This invention relates to an improvement in devices adapted for the convenience and uses of women. It comprises a vanity case in combination with a bouquet holder or dress shield. The article may be carried in 15 the hand by a suitable stem or it may be secured to the corsage of the lady's dress by suitable means.

The invention is illustrated in the accompanying drawings, wherein—

20 Figure 1 is a side elevation in perspective;

Figure 2 is a rear elevation;

Figure 3 is a side elevation; and

Figure 4 is a rear elevation.

25 Referring to the drawings, the parts are designated by numerals, like numerals referring to like parts.

30 1 is a sheet of suitable material such as cardboard of suitable stiffness and flexibility with an oval body portion as 2 with a stem protruding therefrom as 3. I may decorate the periphery of the body portion 2 by ruffled ornamentation which is diagrammatically illustrated as 4. 5 is a flap 35 flexibly secured to the body portion 1 at 6. 7, 7 are the parts of a snap fastener adapted to secure the flap 5 to the body portion 1 and to release the same at pleasure. 8 is a bouquet and 9 the stem thereof, while 10 is a 40 form of pin adapted to secure the stem of the bouquet to the stem 3. It will be understood that this pin 10 may also embrace a portion of the the dress or corsage of the wearer so as to hold the same in position.

45 In Figs. 3 and 4, I have illustrated an alternate form of construction wherein I have extended the base of the flap 5 so as to form a pocketbook of greater comprehensive area than that shown in Fig. 1. In the second

50 form of construction I may surround the flap 5 with a suitable metallic framework as 11, hinged at 12, and clasped at 13, with a dependent pouch as 14. I may also incorporate between the walls of the pocket opening an accordion pleated section at 15 to make the pocket more secure, and this may be done as well in the form shown in Figure 1 as in that shown in Figure 3. Within the pocket formed by the body portion 2 and the flap 5 may be placed or 60 contained small toilet articles such as a mirror, powder puff, etc., as shown at 16 and the pocket may also be used as a receptacle for money, tickets or other articles for which such a receptacle would be adaptable. 65

As previously stated, the invention is susceptible of use either to be held in the hand by the stem, or it may be secured to the corsage, and in this case the body portion 2 and stem portion 3 operate to protect the 70 dress of the wearer against any moisture or other effect of the bouquet. In either case there is easy access to the pocket formed by the flap 5.

I have illustrated the flap 5 as being on 75 the opposite side of the main body 1 from the bouquet, but my invention would be equally useful and adaptable for the purposes intended should the flap be on the same side as the bouquet.

80 I prefer to cover the body portion 2 and the stem 3 and flap 5 with suitable textile material of an ornamental nature, and such textile material may form the flexible connection between the flap 5 and the body portion 1 as at the point 6.

85 It is to be understood that I may form the body portion and stem of two strips of cardboard pasted or otherwise suitably secured together up to the central part of the 90 body portion and thereat laterally crease one of said strips to form the flap.

What I claim is:

1. A vanity case and bouquet holder comprising a sheet of suitable material formed 95 with a body portion and a protruding stem portion or handle, in combination with a pocket flap flexibly connected with said body portion at one edge with means associated with said body portion and with said 100 flap to clasp the same together when said flap is closed upon the body portion or to release the same at pleasure.

105 2. A vanity case and bouquet holder comprising a sheet of suitable material formed with a body portion and a protruding stem portion or handle, in combination with a pocket flap flexibly connected with said body portion at one edge with means associated with said body portion and with said 110 flap to clasp the same together when said flap is closed upon the body portion or to release the same at pleasure, with means to secure said stem portion and the stem of a bouquet to a lady's dress.

3. A vanity case and bouquet holder formed from a sheet of stiff cardboard or similar material, comprising a body portion of oval form and a stem portion protruding therefrom, the periphery of said body portion being adapted to be made ornate, a flap secured to said body portion by a flexible connection, said body portion and stem 10 portion being covered by a textile material, with means to secure the end of said flap opposite to its point of flexible connection with the body portion by a releasable clasp, and means to secure the stem of a bouquet and the stem of the vanity case and protector to the dress of the wearer. 15

Signed my me at New York, N. Y., this 11th day of March, 1922.

SYDNEY B. WERTHEIMER.

Witnesses:

ANDREW J. DALY,
GLADYS NOSSOW.